ROTOR FOR CUTTER-HEADS.

1,396,762.

Specification of Letters Patent. Patented Nov. 15, 1921.

Application filed November 27, 1918. Serial No. 264,385.

To all whom it may concern:

Be it known that I, GEORGE L. KRAMER, a citizen of the United States, and a resident of Portland, county of Multnomah, State of Oregon, have invented a certain new and useful Improvement in Rotors for Cutter-Heads, of which the following is a specification.

My invention relates to portable, pneumatic or air-driven tools; for example, a planer comprising a cutter-head having a rotor, or turbine, fixed on its axle, the rotor being provided with peripheral pockets to receive the impingement of a jet, or jets, of the driving fluid, usually compressed air.

In the making of these tools it was heretofore thought essential that the rotor be given considerable peripheral mass, in order that it would develop momentum, and in this way carry it over the hard spots in the surfaces which it was planing. But I have discovered that the benefit of the momentum so gained was at the expense of acceleration; in other words, it required an appreciable interval of time for the rotor to attain its maximum speed, and to regain its high speed, when slowed down by the work imposed upon it. And, furthermore, since these tools are run at a very high speed, considerable gyroscopic action was developed, due to the peripheral mass of the rotor, so that it imposed considerable muscular exertion on the operator in holding the planer to its work; especially when the tool is used on the sides of a vessel; for which work it is particularly intended.

I further discovered in my experimentation, that the momentum attained by the mass of the rotor may be considered a negligible factor, if the rotor be rendered more susceptible to acceleration so as to develop maximum speed in an instant.

Susceptibility to acceleration is essential because the maximum operative speed of the planer should be attained immediately after the air is turned on. The high speed of the cutter-head is depended upon for efficiency, because the work done consists in cutting away minute particles of the surface at a time; and if the tool encounters hard spots in the surface, and the extra work so imposed reduces its speed, such effect is negligible, provided its operative speed can be recovered by an instant of rest. In other words, the operator, when he en-

counters the hard spots, by simply stopping the planer an instant would permit the tool to regain its maximum speed, so that the hard spots in the surface will offer no appreciable obstacle to the rapidity with which the tool can do its work. Acceleration is also a factor in permitting the tool to regain its maximum speed in the instant of rest which occurs when the operator has finished his stroke in one direction and reverses the stroke.

Since susceptibility to acceleration is one of the conditions of efficiency, it is apparent that unnecessary mass in the part to be rotated introduces a corresponding factor of resistance to acceleration and of inefficiency.

I attain the desired results by reducing the mass, and thus the weight, of my rotor to a practical minimum; that is to say, I make my rotor of a material, aluminum for example, light in weight, and also make it of a shape tending to that end; in short, by the term practical minimum I mean the weight of the rotor shall be reduced as far as practical with regard to the factor of safety; so that by restraining the same unit of driving force that it would have been practical to apply to a rotor of the same dimension but of greater mass, then by reducing the latter to a practical minimum increment in acceleration will be obtained. At the same time by reducing the mass of the rotor its gyroscopic action is greatly reduced, and the tool is rendered more easy to handle.

The embodiment of my invention in practice is illustrated in the accompanying drawings of a portable planer:

Figure 1 is a side elevation of this planer; Fig. 2 is a left-end sectional view with respect to Fig. 1; and

Fig. 3 is a partial sectional side elevation.

In a frame, *a*, is rotatably mounted a cutter-head *b* cored out for lightness, and mounted on the threaded shoulders *c* of two rotors *d*, one of which is located in each side of the tool frame, and the cutter-head is mounted between them. The rotors *d* are provided with stub-shafts *e*, revolving in ball-bearing rings *f*, in the central, annular recesses or boxes of the covers *g*, secured in place by nuts threaded on stud bolts *g'*. Annular chambers *h* of the frame, *a*, extend circumferentially about the rotors, and annular bushings *r* provide fluid-tight closures for the open sides of the fluid chambers *h*

extending circumferentially about and confining the driving fluid to the inlet ports r' of said annular bushings r . A transverse passage-way i connects the annular chambers h .

I use compressed air as the driving force, and the source thereof is connected by a hose with the nipple m .

The frame, a , is made with an integral handle k in which is located a valve for controlling the admission of the air fluid; only the projecting stem l of said valve being shown.

The rotors d , instead of being made of a heavy material—as heretofore was the practice in order to obtain a fly-wheel effect—are made of aluminum, since the latter is at present the lightest material deemed suitable for making the rotors. The latter are also cored out, as at d' , in order to lighten them still more. The peripheries of the rotors are provided with an endless series of pockets n for receiving the impact of the jets of compressed air admitted through the inlet ports r' from the annular chambers h ; a plurality of inlet ports being provided, and the same spaced equal distances apart.

The cutter-head is inclosed by a hood s , having a spout t for discharging the shavings.

At the end a' of the frame the latter is offset in its bearing face from a straight line and preferably at an angle, as shown in Fig. 1, and such offset end is covered by an adjustable shoe o , adjustable relatively to the body of the frame by a screw p threaded into the frame and provided with a lock nut q .

But the details of construction of my tool

are immaterial; my invention merely has for its purpose the carrying into practice of my discovery that in order to have an efficient portable tool of the character described it is essential that the weight or mass of the rotor, or turbine, be reduced to a practical minimum, so as to reduce to a negligible factor the gyroscopic effects and obtain an increment in acceleration from the given unit of driving force, so that the cutter-head may attain and regain its maximum speed in an instant.

The desired new results attained in my improved rotor may be contributed to by avoiding unnecessary mass in the making of the driven part, that is, the cutter-head.

I claim:

1. In a portable fluid driven tool of the character described designed to be manually applied to the work, a rotor made of a light metal thereby adapting the rotor to greater acceleration relatively to a given unit of driving force, and rendering its gyroscopic action a negligible factor.

2. In a portable fluid driven tool of the character described designed to be manually applied to the work, a rotor made of aluminum thereby adapting the rotor to greater acceleration relatively to a given unit of driving force, and rendering its gyroscopic action a negligible factor.

3. In a portable fluid driven tool of the character described, designed to be manually applied to the work, a rotor made of aluminum, cored out and lightened to adapt the rotor to greater acceleration relatively to a given unit of driving force, and to reduce its fly wheel action and to render its gyroscopic action a negligible factor.

GEORGE L. KRAMER.
